Primary Examiner — Kevin K Rudzinski*Assistant Examiner* — Mehri F Bajoul(74) *Attorney, Agent, or Firm* — Global IP Counselors, LLP(57) **CLAIM**

The ornamental design for a litter pan, as shown and described.

DESCRIPTION

FIG. 1 is a front perspective view of a litter pan in accordance with our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the drawings depict portions of the litter pan that form no part of the claimed design.

1 Claim, 7 Drawing Sheets(56)
